UNITED STATES PATENT OFFICE.

WILLIAM C. STEWART, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-LOCATING DEVICE.

1,372,104.

Specification of Letters Patent. Patented Mar. 22, 1921.

Application filed June 12, 1916, Serial No. 103,163. Renewed July 26, 1920. Serial No. 399,178.

To all whom it may concern:

Be it known that I, WILLIAM C. STEWART, a subject of the King of Great Britain, residing at Swampscott, in the county of Essex and State of Massachusetts, have invented certain new and useful Improvements in Sole-Locating Devices; and I do hereby declare the following to be a full, clear, and exact description of the invention, such as 10 will enable others skilled in the art to which it appertains to make and use the same.

The present invention relates to apparatus for accurately locating soles with reference to devices which later operate upon the soles.

15 The object of the invention is to provide certain improvements in sole locating devices of this character which shall insure the accurate and rapid positioning of the sole in the proper relation to the operating instrumentalities. With this object in view, a feature of the invention consists in the provision of two coöperating feelers which are adapted to engage with positioning shoulders formed in opposite sides of the 20 sole edge to locate the sole. In the preferred form of the invention, the coöperating feeler members are adapted to be received in notches formed in opposite sides of the sole edge adjacent the ball line and are constructed and arranged to position the sole 25 both laterally and longitudinally.

Still further features of the invention consist in certain novel features of construction, combinations and arrangements 30 of parts hereinafter described and claimed, the advantages of which will be obvious to those skilled in the art from the following description:

In the drawings illustrating the preferred 35 form of the invention, Figure 1 is a side elevation of a sole molding machine embodying the invention, and Figs. 2, 3 and 4 are details illustrating the gaging mechanism at three different stages in the 40 positioning of the sole.

The illustrated embodiment of the invention is shown in connection with a sole molding machine of the type disclosed in the patent to Preble No. 1,004,076, patented 45 September 26, 1911. This machine comprises an upper mold 10 adjustably mounted upon a fixed cross-head 12 rigidly secured in the machine frame. A lower sole supporting mold 14 is mounted upon a horizontal slide 16 which operates in guideways 55 formed in a vertically movable carrier 18. The lower mold in this type of machine is designed to move from a position of presentation, as shown in Fig. 1, into a position of clearance in alignment with the upper mold 10 and finally into a pressing position in which the sole is engaged between the two molds. The vertical movements are imparted to the carrier 18 by means of a crank 20 on the main driving shaft, which 60 is connected through a link 22 with a toggle having two arms 24 and 26 which are respectively connected with the carrier and with a fixed portion of the machine frame, as shown in Fig. 1. The lower mold is 65 moved into engagement with the upper mold during the vertical movement of the carrier 18, through mechanism consisting of a link 28 connecting the slide 16 with a bell crank 30 which is fulcrumed upon the carrier 18. 70 The bell crank 30 is connected by a link 32 with an arm 34 which is fulcrumed upon the machine frame and is normally moved to retain the slide 16 in the position shown in Fig. 1, through a spring 38. During the 75 initial upward movement of the carrier 18 this mechanism moves the slide rearwardly against the action of the spring until the slide engages with a stop 36 mounted on the carrier. During the continued movement 80 of the carrier the slide is retained in this position by the action of the spring 38.

According to the present invention the flat sole is located accurately with respect to the coöperating molds, through a pair of coöperating gage members which serve to position the sole both laterally and longitudinally. These gage members are provided with feelers which are received in previously formed notches formed in opposite sides of the sole between the ends. The gage members are interconnected in such a manner that as the sole is thrust between them into the proper position on the lower mold the feelers follow the contour of the sole edge 100 until the shoulders formed by the notches are reached, when the further movement of the sole is arrested and the latter is positioned properly with relation to the molds. As shown clearly in Figs. 2 to 4, inclusive, 105 of the drawings, two sole locating gages 40 and 42 are fulcrumed upon a block 44 which is mounted upon the forward end of the

slide 16. The two gages are formed as bell crank levers having inwardly projecting arms 46 and 48 which are provided with intermeshing gear segments to cause equal 5 swinging movements of the bell cranks about their fulcras. The bell crank 40 is provided with an arm 50 removably connected thereto and having a feeler member 52 mounted upon the outer end. This feeler 10 member is longitudinally adjustable through the provision of tongue-and-groove connections with the arm 50 and may be locked in adjusted position on the arm by means of a screw 54. The bell crank 42 is provided 15 with a feeler member 56 which is mounted in the outer end of one arm, as shown clearly in Fig. 2. It will be noted that both of these feeler members are provided with a point which is adapted to engage with the 20 shoulders in the sole edge formed by the notches. The feeler members are normally moved toward one another by a spring 58 which connects the arm 48 with a holding stud 60 threaded in the boss 62 on the block 25 40. This inward movement of the feeler members toward one another may be limited through the provision of a stop screw 64 located in position to engage with the arm 46. This stop screw permits the position of 30 the gages to be so adjusted with relation to one another that a sole may be easily thrust between them on the mold.

With this construction the sole is moved rearwardly, as shown in Figs. 2 and 3, the 35 opposite feeler members following along the contour of the sole edge until the previously formed notches 66 and 68 are reached when the pointed ends of the feeler members enter the notches and indicate the proper locating 40 of the sole. Owing to the fact that the gage members move in unison with one another, they serve to locate the sole laterally upon the mold as well as longitudinally, the provision of the two gage members contacting 45 with opposite sides of the sole also serving to prevent any angular movement of the sole with relation to the molds and obviating the necessity of any additional gage devices. In the position as shown in Fig. 3, the sole 50 is properly located with relation to the ball line 70 of the mold as the shoulders previously formed upon the sole have a predetermined position with relation to the ball line to be molded in the sole and the proper 55 adjustment of the gages may be secured for each different style of sole to be molded. In this connection it will be noted that in addition to the individual adjustment of the feeler member 52 a bodily adjustment of both members may be secured through the provision of longitudinal slots 90 formed in the block 44 which receive fastening bolts 92 threaded into the slide 16.

It is desirable that after the sole has been 59 properly located and clamped in this posi-

tion, the gage members shall be removed from above the mold before the latter reaches a pressing position. To this end the bell crank 40 is provided with an arm 80 having an inclined face which is adapted 70 to engage with a cam roll 82 and rock the two bell cranks 40 and 42 during the inward movement of the slide 16 from a position of presentation into a position of clearance. The roll 82 is supported by a bracket 84 75 adjustably mounted upon the machine frame through a pair of slots 86 which receive securing bolts 88, as shown clearly in the drawings. This construction serves to remove the feeler members and gage arm from the operative position above the lower mold when the latter is moved into alignment with the upper mold. The mechanism for clamping the sole in position upon the lower mold when the operation of the machine is 80 started and prior to the release of the sole by the gage members is clearly described in the Preble patent above referred to and comprises a clamping arm 72 which is pivoted to the slide 16 and is actuated from a stationary slotted clamp plate 78 which receives a roll 76 journaled upon the clamp arm. The clamp plate 78 is mounted on the carrier 18 and as the slide 16 moves horizontally operates to bring the clamp down upon the 85 heel end of the sole in the manner well known to those skilled in the art.

Although the illustrated embodiment of the invention is illustrated in connection with a sole molding machine it is obvious 100 that certain features of the invention are applicable to any type of machine in which the sole is to be located with relation to devices which are to later operate upon the sole.

While it is preferred to employ the specific construction and arrangement of parts shown and described, it will be understood that this construction and arrangement is not essential except so far as specified in the 105 claims, and may be changed or modified without departing from the broader features of the invention.

The invention having been described, what is claimed is:

1. A machine for operating upon shoe soles, having, in combination, devices with relation to which a sole is located before being operated upon, and means for locating a sole in proper position with relation to said devices, including a feeler arranged to bear against and follow the edge contour of the sole as the sole is moved past the feeler and shaped to engage a shoulder on the edge to determine the longitudinal position of the sole.

2. A sole molding machine, having, in combination, sole pressing molds and means for locating a sole in proper position with relation to the molds, including a feeler co- 130

operating with the edge contour of the sole and shaped to engage a shoulder on the sole edge and determine the longitudinal position of the sole.

- 5 3. A sole locating device for machines for operating upon shoe soles, having, in combination, sole centering members acting on opposite sides of the sole edge intermediate its ends, and a feeler carried by one of said members arranged to bear against and follow the sole edge and shaped to engage a shoulder on the contour of the sole edge as the sole is moved past the feeler to determine the longitudinal position of the sole.
- 10 4. A sole locating device for machines for operating on shoe soles, having, in combination, sole centering members acting on opposite sides of a sole edge intermediate its ends, and a feeler carried by each of said members arranged to bear against and follow the sole edge and shaped to engage shoulders on the contour of the sole edge as the sole is moved past the feeler to determine the longitudinal position of the sole.
- 15 5. A sole molding machine, having, in combination, sole pressing molds, means for locating a sole in proper position with relation to the molds, including a feeler coöperating with the edge contour of the sole to determine the longitudinal position of the sole, and means by which the feeler may be adjusted longitudinally of the molds.
- 20 6. A sole molding machine, having, in combination, sole pressing molds, sole cen-

tering members acting on opposite sides of the sole intermediate its ends, feelers carried by said members to coöperate with the edge contour of the sole, and means for adjusting one of said feelers longitudinally of the molds relatively to the other feeler.

25 7. A sole molding machine, having, in combination, sole pressing members, sole centering members acting on opposite sides of the sole intermediate its ends, a feeler carried by one of said members constructed and arranged to bear against and follow the sole edge and shaped to engage a shoulder on the contour of the sole edge as the sole is moved past the feeler, and means for adjusting the centering members longitudinally of the pressing members.

30 8. A machine for operating on shoe soles having, in combination, devices for performing a predetermined operation upon a sole, and a pair of oppositely disposed feelers designed to engage previously formed notches in the sole edge to locate the sole longitudinally.

35 9. A machine for operating on shoe soles having, in combination, devices for performing a predetermined operation upon a sole, a pair of oppositely disposed feelers designed to engage previously formed notches in the sole edge to locate the sole longitudinally, and connected mechanism for causing the feelers to center the sole laterally.
